BATTERY TERMINAL CONNECTOR

Joseph J. Knasko and Michael Gribik,
Ford City, Pa.

Application November 5, 1947, Serial No. 784,248

3 Claims. (Cl. 173—259)

1

This invention relates to battery terminal connectors, and more especially to such connectors for use on automobile storage batteries.

As is well known, storage batteries are provided with upstanding tapered terminal posts formed of lead, and the battery cable is connected to the positive post by means of a split sleeve provided with a nut for clamping it tightly about the post. This conventional type of terminal connector has been in use for many years and is quite unsatisfactory because of the corrosion which occurs between the split sleeve and the post and which also occurs around the clamping bolt, thus making it extremely difficult to loosen the bolt and to remove the split sleeve from the battery post, when necessary.

An important object of the present invention is to provide a novel type of battery terminal connector by means of which a highly effective electrical connection is made and by means of which terminal corrosion is eliminated.

A further object is to provide a terminal post connector formed of a plurality of parts whereby improved electrical connection is made between the battery cable and terminal post, and wherein novel lubricating means is employed for lubricating any contacting portions of the various elements and for sealing such portions from contact with the atmosphere, thus eliminating corrosion and permitting the terminal connection to be readily removed.

A further object is to provide a device of the character referred to, wherein threaded means is employed for securing a highly effective electrical connection with the battery post, and wherein a single grease fitting is adapted to provide for the lubrication of the various parts, including the threaded means, thus preventing corrosion and permitting the easy removal of the terminal connection.

Other objects and advantages of the invention will become apparent during the course of the following description.

In the drawing we have shown several embodiments of the invention. In this showing:

Figure 1 is a central vertical sectional view through one form of the invention shown in position on a battery terminal post, parts being shown in elevation.

Figure 2 is a detail sectional view on line 2—2 of Figure 1.

Figure 3 is an enlarged sectional view on line 3—3 of Figure 1, the battery post being omitted.

Figure 4 is a view similar to Figure 1, showing a modified form of the invention.

2

Figure 5 is a sectional view on line 5—5 of Figure 4.

Figure 6 is a view similar to Figure 1 showing another modification of the invention, and,

Figure 7 is a sectional view on line 7—7 of Figure 6.

Referring to Figures 1, 2 and 3, the numeral 10 generally indicates the conventional automobile storage battery having a positive terminal post 11 to which a conventional cable 12 is to be electrically connected. The post 11, in accordance with conventional practice, is preferably formed of lead, and accordingly is relatively soft.

The present invention comprises a sleeve 15 having a radial projection 16 forming a socket in which the wire 17 of the cable 12 terminates and within which such wire is soldered to form a permanent connection. The sleeve 15 is internally threaded as indicated as a whole by the numeral 18. These threads are cut from the top of the sleeve 15 by a suitably shaped die whereby the inner limits of the threads throughout the greater portion of the height of the sleeve 15 lie in a cylinder coaxial with the sleeve 15. The lowermost thread 18, and preferably the two lowermost threads, progressively decrease in diameter, it being apparent in Figures 1 and 3 that these lowermost threads project radially inwardly further than the innermost portions of the threads thereabove. The inward tapering of such lowermost threads is substantially as indicated by the broken lines 19. The die used for cutting the threads 18 will be suitably shaped to form the threads 18 as described. The sleeve 15 rests upon a sealing washer 19' formed of any soft resilient material.

An intermediate sleeve member indicated as a whole by the numeral 22 is provided with a solid upper portion 23 arranged above the battery post 11. The head 23 carries integral depending fingers 24 defining a sleeve arranged between the sleeve 15 and the battery post 11, the fingers being separated by slits 25 extending up to the head 23.

The sleeve member 22 is formed of any suitable material, preferably harder than the lead of which the post 11 is formed, for a purpose to be described. For example, the sleeve member 22 may be formed of copper or suitable copper alloy. The sleeve member 22 is externally threaded throughout its length as at 26, these threads having the same pitch and depth as and being engageable with the threads 18. However, the threads 26 are of uniform diameter throughout the length of the sleeve member 22 and when the sleeve member 22 is screwed downwardly beyond the position shown

in Figure 3, to its fully applied position, the lower tapered threads 18 will force the lower ends of the fingers 24 inwardly for a purpose to be described.

The sleeve formed by the fingers 24 is internally threaded as at 28. These threads need not be of any particular formation but they should be of the same pitch as or of slightly greater pitch than the threads 26 for a reason which will become apparent. The internal threads 28, when the sleeve member 22 is screwed downwardly in the sleeve 15, cut threads 29 on the outer surface of the battery terminal 11, as shown in Figure 1.

The head 23 of the sleeve member 22 is provided with an upstanding polygonal boss 39 for engagement with a wrench whereby the sleeve member 22 may be turned downwardly into position. A conventional grease fitting 31 is carried by the boss 39 and is adapted for connection with a suitable grease gun to force grease downwardly through an opening 32 in the head 23, and into the space 33 between the upper end of the post 11 and the bottom face of the head 23. If desired, the fitting may be an integral part of the head 23; that is, the latter itself may be shaped as a grease fitting.

In the form of the invention shown in Figures 4 and 5, a split sleeve 35, formed of complementary sections 36 and 37, is provided with a tapered inner surface 38 adapted to fit the battery post 11. The sleeve 35 may be split as at 39 from top to bottom, or through any desired vertical distance from the top. The sleeve section 37 is provided with a conventional radial projection 40, similar to the projection 16, and to which the battery cable 12 has its wire 17 connected in the usual manner.

Above the projection 40, the sleeve 35 is externally threaded as at 42 for reception in the internally threaded depending sleeve 43 of a cap 44. This cap holds the elements 36 and 37 in assembled positions, gripped in electrical engagement with the post 11. The upper portion of the cap 44 may have its outer surface 45 polygonally shaped for engagement with a suitable wrench.

A conventional grease fitting 46 is adapted to supply grease through an opening 47 to a space 48 above the post 11, the threads of the sleeves 35 and 43 and the upper end of the post 11 thus having access to the source of grease supplied through the fitting 46.

A further modified form of the invention is shown in Figures 6 and 7. In such form of the invention a unitary cap 50 is provided with a depending sleeve 51 at one side of which is a projection 52 having connection with the battery cable 12. The sleeve 51 is adapted to be arranged over the battery post 11. The recess 53 within the cap 50 has one side 54 shaped to fit around the adjacent side of the post 11. The opposite side of the recess 53 is laterally enlarged as at 55 and the side walls of the recess are connected by a substantially semi-circular portion 56 eccentric to the post 11 and spaced a substantial distance therefrom.

A clamping member 60 is arranged in the enlarged recess portions 55 and 56 and has its inner surface 61 shaped to fit the post 11. The surfaces 54 and 61, or either of such surfaces, may be serrated or roughened as shown in Figure 6 for effective engagement with the post 11, and to provide grooves for the passage of lubricant for a purpose to be described. The screw 62 is threaded in an opening 63 and carries a

wrench engaging head 64 at its outer end. The inner portion of the screw 63 has a reduced shank 65 extending through and rotatable in the clamping member 60. The end of the shank 65 is headed as at 66 to prevent its displacement from the clamping member 60. One side of the opening 63, and preferably the top side, is milled out or otherwise provided with a groove 67 for a purpose to be described.

10 A grease fitting 70 is carried by the cap 50 and supplies grease through an opening 71 connected to the space 72 above the post 11. This grease is free to circulate around the clamping member 60, and when the interior of the device is filled, 15 some of the grease will be forced through the small groove 67 to lubricate the screw 62 and to assist in sealing the opening 63 against the entrance of air.

Operation

20 The form of the invention shown in Figures 1, 2 and 3 is preferred to the other forms and has been found in practice to provide exceptional and extremely efficient results. In assembling the device for the first time, the washer 19' which 25 is preferably employed to seal the lower end of the device completely against the entrance of air, is placed in position around the base of the post 11. The sleeve 15 is then placed around the post whereupon the sleeve member 22 has the sleeve 30 portion inserted in the upper end of the sleeve 15 and may be initially turned by hand to move it downwardly to the point where the lower extremities of the fingers 24 extend below the upper end of the post 11 with the threads 28 contacting 35 with the post 11. Some slight pressure is preferably exerted downwardly on the sleeve 15 to slightly compress the washer 19' while the sleeve member 22 is being rotated by a wrench applied to the polygonal projection 30.

40 As previously stated, the material of the sleeve member 22 is substantially harder than the soft lead of the post 11. As the wrench applied to the projection 30 is turned, the threads 28 will cut or shape threads in the battery post 11. 45 Threads 18 and 26 will be in engagement with each other, and the threads 28 are pitched preferably the same as the threads 18 and 26 for a purpose to be referred to later. Lubricant may be supplied through the fitting 31 during the 50 operation of cutting the threads on the post 11, thus facilitating the cutting of such threads with the expenditure of less force in turning the sleeve member 22. Rotation of the latter member is continued until the lower ends of the 55 fingers 24 reach a position in engagement with the uppermost of the tapered threads 18, that is, approximately to the position shown in Figure 3. The sleeve member 22 is then removed and lead cuttings are cleaned out of the cable connection. 60 With grease supplied to the space 33, a wrench is applied to the projection 30 to screw the sleeve member downwardly to operative position. The threads 28 will follow the threads 29 cut in the post 11, as will be apparent. As the fingers 24 move downwardly beyond the point shown in Figure 3, the tapered threads 18 at the bottom of the sleeve 15 will progressively force the lower ends of the fingers 24 inwardly to cause the lowermost threads 28 to "bite" rather deeply into the post 11 to insure an even tighter electrical connection between the sleeve 22 and post 11. 65 The threads 18 and 28 in Figure 3 are intended to be shown only approximately of the same pitch. If these threads are pitched exactly alike, 70 the operation will be as described above. If the

pitch of the threads 28 is slightly greater than the pitch of the threads 18 and 26, the downward turning of the cap 22 will cause the sleeve 15 to be bodily moved slightly downwardly, and this movement may be utilized to tightly compress the washer 19'.

The lubricating of all of the surfaces by the single grease fitting 11 serves not only to facilitate the assembly of the parts by lubricating them, but also coats all of the contacting faces of the parts with grease, thus sealing them against the action of the atmosphere and preventing corrosion which so commonly occurs and causes so much trouble in connection with the removal of battery terminal connections. Moreover, the presence of the grease provides for the easy unscrewing of the sleeve member 22, when necessary. It will be apparent that the grease will be supplied to the threads 18 and 26 and to the threads 28 and 29, and some of the grease readily may be forced downwardly into contact with the washer 19' to seal the lower end of the device to the atmosphere.

The cutting of the threads 28 is important for two reasons. In the first place, it provides far more efficient electrical connection between the sleeve 22 and post 11. In the second place, it will be apparent that if the inner surfaces of the fingers 24 were smooth and corresponded in shape to the outer surface of the post 11, the screwing down of the sleeve member 22 in the sleeve 15 would continue until substantial friction developed between the fingers 24 and post 11 to oppose further downward movement of the sleeve member 22. Unless extreme pressure were applied at the top of the device, therefore, the turning of the threads 26 in the threads 18 would result in moving the sleeve member 15 upwardly instead of moving the fingers 24 downwardly. This would prevent the establishment of a perfect electrical connection for the battery post and would provide two other serious disadvantages. First, the contacting conical surfaces of the post 11 and fingers 24, under the shaking and vibratory actions due to the moving of the vehicle would cause the fingers 24 to slip upwardly. Secondly, the upward movement of the sleeve 15 would permit the entrance of air into the bottom of the device.

The form of the invention shown in Figure 4 has been found very satisfactory but not as highly efficient in continued operation. As in the form described above, the cap 44 exerts a direct radially inward force to press the complementary members 36 and 37 into firm engagement with the battery post. Prior to the tightening of the parts, some grease will be forced through the fitting 46. Some of this grease will flow downwardly around the post 11, and some will find its way into the threads 42, thus sealing the contacting parts of the device from the atmosphere.

In the form of the device shown in Figures 6 and 7, grease is forced through the fitting 70 with the clamping members 60 slightly spaced from the post 11. Thus the post will be coated with grease and the lubricant will escape around the clamping member 60 and into the recess portion 56. The grooves formed by the serrations 61 permit the free flow of lubricant around the post 11. A small amount of the grease will be forced through the opening 67 and the appearance of grease at the outer end of this opening will indicate that sufficient lubricant has been forced into the device.

The nut 64 is then turned with a wrench to move the clamp member into engagement with the post, the latter being clamped between the inner surfaces of the member 60 and the recess surface 54. Thus efficient electrical connection will be established and all of the parts will be sealed with lubricant.

The turning of the screw 62 after lubricant has been applied in the manner stated causes the threads of the screw to carry lubricant around the opening 63 to make the latter leak-proof as to the entrance of the atmosphere. The smaller amount of lubricant forced through the opening 67 incident to the shaking and vibrating of the material and the softening of the lubricant by the absorption of heat from the vehicle engine, will cause the lubricant to gradually flow around the screw 62 to more effectively seal the outer end of the opening 63.

In each form of the invention a very efficient clamping action against the battery post is provided by the employment of a plurality of parts, and all of the contacting surfaces of all of such parts are adequately lubricated through the provision of a single grease fitting. Each form of the invention includes screw threaded means for effecting the clamping action, and the threads of such means are lubricated and protected by the grease forced into the device. In practice, it has been found that after substantial periods of operation, the terminal connections can be just as easily removed as they can when the devices are first placed in position, and it has been found that corrosion of the parts is substantially completely eliminated.

While it is preferred that the various grease fittings be employed for convenience, each of the cap members employed can be filled with grease prior to being placed in position. While satisfactory results thus can be obtained, it is impossible to predetermine the exact amount of grease which will be required, and for this reason and because of the cleanliness involved, it is preferred to employ the grease fittings for introducing the lubricant.

The use of the washer 19' is preferred, but it may be omitted as in Figures 4 and 6 and the grease forced downwardly around the terminal posts may be depended upon to seal the lower end of the device to the atmosphere. The washer 19', however, forms a more efficient sealing means.

As previously stated, the form of the invention shown in Figure 1 is preferred. One important reason for this is that the screwing of the cap 22 on the post 11 effectively cleans oxidation from such post and leaves clean lead surfaces for perfect electrical connection with the threads 28.

It will be noted that each form of the invention involves the use of a plurality of parts relatively movable into clamping engagement with the battery post by operation of threaded means. In Figures 1, 2 and 3, the relatively movable elements engageable with the post 11 are the fingers 24. In Figures 4 and 5, such elements are the relatively movable sections 36 and 37, while in Figures 6 and 7, such elements are the cap 51 and clamping member 60. The threaded means for effecting the clamping action are the threads 18 and 26 in Figure 3, the threads 42 and the internal threads of the sleeve 43 in Figure 4, and the threaded shank 62 and the threads in the opening 63 in Figures 6 and 7. It also will be noted that each form of the invention involves a plurality of parts which completely house the battery post to completely seal the latter, assisted

by the lubricant, from the action of the atmosphere. It further will be noted that regardless of the number of parts which go to make up each device, a single grease fitting provides lubricant for all of the parts to make it possible to seal the post 11 from the atmosphere.

We claim:

1. A terminal connector for a battery post comprising an internally threaded sleeve of larger internal diameter than and adapted to surround a battery post, and a cap member threaded in the upper end of said sleeve and having integral depending fingers threaded in the interior of said sleeve, the space between said sleeve and the outer surface of said post decreasing in size downwardly whereby the downward turning of said cap member will cause said fingers to be forced radially inwardly into clamping engagement with the battery post, said fingers having threads formed in their inner surfaces pitched similar to the threads in said sleeve to cut threads in the battery post upon downward turning movement of said cap member, the internal diameter of said sleeve member adjacent the lower limit of movement of the lower ends of said fingers decreasing in diameter whereby, as the lower ends of said fingers approach their lowermost limit, they will be forced inwardly into engagement with the battery post.

2. A terminal connector for a battery post comprising an internally threaded sleeve of larger internal diameter than and adapted to surround a battery post, a cap member threaded in the upper end of said sleeve and having integral depending fingers threaded in the interior of said sleeve, the space between said sleeve and the outer surface of said post decreasing in size downwardly whereby the downward turning of said cap member will cause said fingers to be forced radially inwardly into clamping engagement with the battery post, said fingers having threads formed in their inner surfaces to cut threads in the battery post upon downward turning movement of said cap member, and a deformable sealing washer arranged between the lower end of the sleeve and the top of the battery, the threads on the inner surfaces of said fingers being of slightly

5 10 15 20 25

greater pitch than the threads on said cap member and said sleeve whereby the latter will move downwardly and deform said washer when said cap member is turned downwardly.

3. A battery terminal connector for a battery post comprising a vertical open-ended sleeve larger in internal diameter than the battery post to surround the battery post, and a cap member having a depending sleeve portion formed integral therewith, such sleeve portion of said cap being externally threaded for reception through the top of said open-ended sleeve and being internally threaded, the sleeve portion of said cap having substantially radial slots cut therethrough and dividing the internal threads thereof into relatively sharp-ended sections to cut the material of the battery post when said cap is screwed into the top of said open-ended sleeve when the latter surrounds the battery post, said open-ended sleeve being of such height that when said cap is screwed down onto the battery post, said open-ended sleeve covers said slots whereby said open-ended sleeve and said cap form a grease-retaining housing for the battery post.
